CLAIM

The ornamental design for a liquid container, as shown and described.

DESCRIPTION

FIG. 1 is a top perspective view of a sleeve for a liquid container showing our new design;

FIG. 2 is a bottom perspective view thereof;

FIG. 3 is a rear view thereof;

FIG. 4 is a front view thereof;

FIG. 5 is a left side view thereof; and,

FIG. 6 is a right side view thereof.

The broken lines in the drawings depict portions of the sleeve for a liquid container that form no part of the claimed design.

In other embodiments of our design, the dashed lines indicating any one or more unclaimed feature(s) of the first or second embodiments of our design may be replaced with solid lines to claim any one feature or combination of features.
